CLAIM

The ornamental design for a support material removal system, as shown and described.

DESCRIPTION

FIG. 1 is a front side view of a support material removal system showing our new design;

FIG. 2 is the right side perspective view thereof;

FIG. 3 is the right side view thereof;

FIG. 4 is the left side view thereof; and,

FIG. 5 is the top plan view thereof.

The broken lines in the drawings depict portions of the support material removal system which form no part of the claimed design.
